UNITED STATES PATENT OFFICE.

ABRAHAM H. VAN SCIVER, OF PROVIDENCE, RHODE ISLAND.

OYSTER-DREDGE.

1,172,325.

Specification of Letters Patent. Patented Feb. 22, 1916.

Application filed June 18, 1914. Serial No. 845,759.

To all whom it may concern:

Be it known that I, ABRAHAM H. VAN SCIVER, citizen of the United States, residing at Providence, in the county of Providence 5 and State of Rhode Island, have invented certain new and useful Improvements in Oyster-Dredges; and I do hereby declare the following to be a full, clear, and exact description of the invention, such as will enable others skilled in the art to which it 10 pertains to make and use the same.

My invention relates to an improvement in oyster dredges.

Heretofore, as is shown in my Patent 15 590,712, dated September 28, 1897, it has been the custom to form the neck of dredges by an elongation of the side frames and center bar and rivet these elongated parts together. This has proved the weakest part 20 of the dredge, as the break always occurs through the rivet holes of the neck. When the dredge breaks at this point, it is necessary to make a new set of side frames entire, in fact, practically rebuild the dredge.

25 In my improved dredge the neck is solid, and the center bar is integral with the neck and a continuation of the same. The upper and lower side frames are riveted to the center bar back of the neck portion. Dredges 30 are hauled in when the vessel is going at full speed, and the part of the dredge to first strike the roller on the vessel is the neck, which it does with a force sufficient in a short time to fracture a built up neck, which 35 cannot occur in a solid one.

40 Referring to the drawings—Figure 1 represents a side elevation of the dredge; Fig. 2 is an enlarged detail side elevation of the integral neck and center bar; Fig. 3 is an enlarged detail upper plan view of the integral neck and center bar; Fig. 4 is an upper plan view of the dredge with the shoes 45 of the lower side frames omitted; and Fig. 5 is an enlarged detail broken side elevation of the rear end of one of the lower side bars.

The principal improved feature of the dredge, over the structure shown in my above-identified patent, lies in the solid neck 50 1 round in cross section the better to pass over the roller of a vessel (not shown). The flat portion 2 back of the neck and integral therewith serves the purpose of a center bar connected to the cross brace rod 3 secured to the two upper side frames 4 and 5. These side frames are attached to the wider part

2^a of the center bar by the rivets 6 passing through holes 7, Fig. 2 of the center bar. The lower side frames 8 and 9 are also secured to the lower portion of the widened 60 part of the center bar by the rivets 10 passing through holes 11, Fig. 2. When these upper and lower side frames are thus secured to the center bar as shown, the wider part 2^a of said bar will project above the 65 neck and the forward connecting point of the lower side frames to form the comb 12. This comb serves the purpose of righting the dredge should it be hauled in bottom side 70 up. In other words, if the dredge should come in bottom side up, this narrow comb in contacting with the horizontal roller of the vessel (not shown) will roll the dredge over. This righting movement is assisted by the contact of the apex *a* of the angle 75 formed by the upper side frames with the center bar 2 when said apex contacts with the vertical roller (not shown) on the boat.

The lower side frames connect with the blade 13, carrying the teeth 14, through the 80 medium of the bolts 15. The side bows 16 and 17 also connect the upper side frames 4 and 5 with said bolts. A shoe 18, one only being shown, is attached to the rear end of the lower side frames and to the bolts 15 to 85 protect the teeth when the dredge passes over the ship's roller.

The upper side frames 4 and 5 are made of angle iron to impart both strength and lightness to the dredge and are connected 90 to the center bar 2 by the braces 19 and 20. Cross braces 21 and 22 stiffen the lower side frames and four vertical braces—two, 23 and 24, Fig. 1, only being shown—firmly 95 connect the upper and lower side frames together. The brace rod 25 connects the blade with the forward end of the center bar 2, as shown.

As is shown in my Patent No. 590,712, heretofore the lower side frames, from their 100 connection at the neck and blade, have been made straight. This arrangement threw the neck down and the blade in a vertical position which caused the dredge to draw on its heels and consequently hard. I have 105 overcome this trouble by forming an upward bend in these lower side frames intermediate of their ends at about the point *b*, Figs. 1 and 5. This will carry the neck of the dredge up and also bring the blade 110 13 in a horizontal position and cause the dredge to draw easier. The teeth project-

ing downward at right angles to the blade and the horizontal position of the blade will serve to limit the depth of the teeth in the mud or sand, and more oysters will thus be gathered at a single haul.

From the foregoing description it will readily be seen that lightness and strength are combined in my improved dredge, and its lasting qualities greatly enhanced 10 thereby.

Having thus described my invention, what I claim is:

1. In a dredge of the character described, comprising a solid neck and center bar 15 combined in one piece, the forward part of the center bar elevated above the neck to form a dredge-righting comb, and side frames connected to the center bar.
2. In a dredge of the character described, 20 comprising a solid neck and center bar of one piece of metal, the center bar being flattened and having the forward portion thereof elevated above the neck to form a dredge-righting comb, upper side frames 25 made of angle iron whose forward ends are secured to the comb portion of the center bar and whose upper faces are practically on a line with the upper edge of the center bar, a toothed blade, and bows connecting the blade with said upper angle iron side frames.
3. A dredge comprising a neck and center bar formed from a single length of

material, the neck being rounded and the center bar being flattened, said bar being 35 widened adjacent the neck to provide an outwardly projecting dredge-righting comb, side frames having their ends connected to the center bar, and a scraper bar carried by the side frames.

4. A dredge comprising an integral neck and center bar, upper and lower side frames having their forward ends connected to the center bar adjacent the neck, a scraper bar 40 connected to the rear ends of the side 45 frames, and scraper bar shielding shoes carried by the rear portions of the lower side frames.

5. A dredge comprising a neck formed of a single piece of material that is trans- 50 versely rounded and having a flattened center bar projecting rearwardly therefrom, and side frames attached to the center bar.

6. A dredge comprising a neck and a center bar integral therewith, the neck being transversely rounded and longitudinally curved, the center bar being flattened, and side frames attached to the bar in 55 proximity to the neck.

In testimony whereof I affix my signature 60 in presence of two witnesses.

ABRAHAM H. VAN SCIVER.
